UNITED STATES PATENT OFFICE

LOUIS H. SCHLEICHER, OF ST. LOUIS, MISSOURI

BOX

Application filed July 15, 1929. Serial No. 378,210.

This invention relates to boxes and has special reference to boxes of the type used as receptacles for candy or bakery products or articles of different kinds.

5 The invention relates particularly to a device in connection with the lid or cover of the box and including a hinged side or wall member adapted to be folded in flat relationship upon or above the lid or cover of 55 the box when not in use so as to enclose and confine thereunder articles or materials of different kinds, said side or wall member capably being raised to permit access to the articles, and means for retaining said side 10 or wall member in flat relationship upon or over the box lid or cover.

Another object of the invention is to provide, in connection with a box, an article receptacle in connection with the lid or cover 20 of the box and including a hinged side or wall member adapted to be folded on or over the lid or cover of the box or raised or turned away from said box lid or cover, in combination with article holding devices between said 25 side or wall member and said lid or cover of the box, and means in connection with the box lid or cover for holding said side or wall member in closed position.

Other objects will appear from the following description, reference being made to the accompanying drawings in which

Fig. 1 is a top plan view of a box having my invention in connection therewith and parts being broken away to illustrate several 35 features of the device.

Fig. 2 is an end elevation of the box with the hinged side or wall member raised slightly.

Fig. 3 is a reduced top plan view of the 40 box showing the hinged side or wall member open.

The box, in connection with which the present invention is shown, comprises a bottom wall 1, a side wall 2 rising from the bottom wall 1 and forming an enclosure which 45 is open at the top. The lid or cover for this box comprises a top member 3 having, in connection therewith, a side wall 4 designed and adapted to telescope about and enclose 50 the box wall 2. In order to provide an or-

namental structure, the top member 3 has secured to the upper side thereof a padded surface forming device 5, although this feature may be omitted or not, as desired. A base 6 is shown as attached to the part 55 in centered position, the edges of said base 6 being spaced inwardly. This member 6 may be omitted or not as desired.

My present invention comprises an article receptacle or holder secured to the lid or 60 cover of the box and in the embodiment shown comprises a wall forming member 7 seated upon and secured to the base 6 by fastening means, such as glue. The front marginal portion of the wall member 7 is 65 folded rearwardly upon said wall member to provide a wall 8 along the side marginal wall 7. The ends of the wall 8 are attached to the ends of the wall 7 by glue 9 or other fastening means. This leaves the rear edge 70 of the wall 8 between the end fastening means 9 detached and separate from the wall 7 and provides a receptacle for receiving and retaining articles, such as the ends or 75 edges of pieces of stationery 10.

The sheet of material comprising the walls 7 and 8 is of sufficient length to provide an upper side or wall member 11, which, as shown, is of about the same length as of the length and width of the wall 7. The walls 7 and 11 are united along their rear edges by a hinge 12, which may comprise a foldable portion of the sheet of material of which said wall members 7 and 11 are formed. That is to say, the sheet of material may be folded 80 along a line to provide the hinge 12 and to permit the wall member 11 to lie flat above or upon the wall 7, as shown in Fig. 1, or raised and turned back, as shown in Fig. 3. The forward edge of the wall member 11 is 85 folded under to provide a wall portion 13 integrally united with the wall 7 along the line 14 and having its ends secured or fastened to the wall 11 by fastening means 15, which may be glue. This provides a receptacle between the walls 11 and 13 approximately the full length of the walls 11 and 13 designed and adapted to receive and contain articles, such as the edges of pieces of stationery 16. Thus, the envelopes of the 90 100

stationery for correspondence purposes may have their edges inserted in the pocket between the walls 7 and 8 or in the pocket between the walls 11 and 13; while the sheets of paper of the stationery may have their edges inserted in the other pocket. In this way, one of said pieces, such as the envelopes, is held by the stationery pocket and the other of said pieces of stationery is held and supported in the other pocket. So when the side or wall member 11 of this device is raised and turned rearwardly, the articles in the stationery pocket and also the articles carried by the side or wall member 11 are exposed and are readily removable for use.

A device for holding or retaining the side or wall member 11 in proper closed and flat position is provided. As shown, this device comprises a ribbon or tape 17 having its ends secured under the marginal portions of the member 5 and extending diagonally across one of the corners of this device so that when the hinged lid or cover 11 is folded to closed position, it is necessary to extend and project one of the corners of said side or wall member 11 under the device 17. In this way, the wall member 11 is held in closed position by the ornamental device 17 and is readily withdrawable from engagement with said device 17 in order to open the receptacle and give access to its contents.

As shown, the wall member 11 has therein a rectangular series of slits 18 designed and adapted to receive the corners of a card 19 bearing a pictorial design, if desired. The corners of this card 19 may or may not be fastened in the positions in which they are placed in the slits 18 according to preference. In some instances, it may be preferable to permit removal of the card 19 and interchange therewith or substitute therefor other pictorial illustrations.

From the foregoing, it is now clear that I have provided a box for use as a receptacle or container and which, after being sold by the dealer with or without edible contents or other articles, still constitutes a useful article to the customer, even after the contents of the box are exhausted. The use of the box as a container for articles may be continued and the foldable receptacle on the top of the box constitutes a highly ornamental and useful feature.

I am aware that the invention may be varied in numerous particulars without departure from the nature and principle thereof. I do not restrict myself in any unessential respects but what I claim and desire to secure by Letters Patent is:

1. A device of the character described comprising a lid member, an element fixedly secured to the upper side of the lid member forming a pocket opening away from the front edge of said element, a wall member hinged to the opposite edge of said element

for pivotal movements to flat position upon said pocket and to open position away from said pocket, and a device attached to said lid member and extending diagonally across one corner of said element and said pocket 70 and adapted to be engaged over a corresponding corner of said wall member to hold said wall member upon said pocket.

2. A device of the character described comprising a support, an element secured to the upper side of said support, a wall member hinged to the rear edge of said element for swinging movements toward and away from said element, a pocket along the edge of said element opposite from and opening toward 80 said hinge connection, a pocket along the free edge of said wall member opening toward said hinge connection, and a device attached to said support and extending across said wall member for holding said wall member 85 upon said element.

3. A device of the character described comprising a support, an element secured to the upper side of said support, a wall member hinged to the rear edge of said element for 90 swinging movements toward and away from said element, a pocket along the edge of said element opposite from and opening toward said hinge connection, a pocket along the free edge of said wall member opening toward 95 said hinge connection, and a device having its ends attached to said support and having its intermediate portion extending across a corner portion of said wall member and releasably holding said wall member 100 upon said element.
